Fig. 2. being a cross section of the same.

The case has horizontally the oblong octagonal form seen in fig. 1.

Each facet is ornamented by a panel b'. The places for the screws a, and handles b, are decorated by diamond formed fluted or beaded scutcheons g. The lid has a depressed ogee rim d and raised panel e with concave sides e'. The opening for the face plates or light, is skirted by a raised moulding e''', and the central portion of the cover is graced by two further elevated panels e'' & e'''.

I claim as new and of my invention the design of a metallic burial case as described and represented.

In testimony of which invention I hereunto set my hand.
